UNITED STATES PATENT OFFICE.

TOMBAY TANAKA, OF SACRAMENTO, CALIFORNIA.

MILK-BOTTLE CAP.

Application filed June 20, 1924. Serial No. 721,233.

To all whom it may concern:

Be it known that I, TOMBAY TANAKA, citizen of Japan, residing at Sacramento, in the county of Sacramento and State of California, have invented certain new and useful Improvements in Milk-Bottle Caps, of which the following is a specification.

The present invention relates to bottle closures, and particularly to paper-cap closures for milk bottles. The object of the invention is to provide in combination with a milk bottle cap, a simple and cheaply constructed device which will enable the cap to be easily removed without likelihood of injury thereto.

Referring to the accompanying drawings: Figure 1 is a top plan view of a bottle cap having my invention applied thereto, and Figures 2 and 3 are sections taken on the lines 2-2 and 3-3 of Figure 1.

In the drawings, the numeral 10 designates a paper cap such as is ordinarily used for closing milk bottles, except that it is not provided with the usual finger-hold tab, and is formed with a central aperture 11. Passing through the aperture 11 is a flexible member, or string, 12, which has a bight 13, engaging an edge of the disk. The end portions of this string are folded around the diametrically opposite edge of the disk at 14, and are brought over the disk and terminate at a point well beyond aperture

11. In order to secure the end portions of the string, and to seal the aperture, I provide a relatively small disk 15, of paper or similar material pasted over the aperture and over the end portions of the string, the free ends of the string projecting from this disk, to provide a finger-hold for removing the cap.

The device obviously provides a very simple and convenient means for removing from a milk bottle its paper cap without danger of tearing or otherwise injuring the cap.

Having particularly described my invention, what I claim as new and desire to secure by Letters Patent of the United States is:

In combination with a disk closure for milk bottles and the like provided with a central aperture a string passing through said aperture and having a central bight engaging an edge of the disk and having its end portions folded around the opposite edge and extending over the disk substantially beyond said aperture, and a relatively small disk of paper pasted over said aperture and over said end of portions with the free ends of the string projecting therefrom.

In testimony whereof I hereunto affix my signature,

TOMBAY TANAKA.
